UNITED STATES PATENT OFFICE.

ALFRED J. KNIGHT, OF MELROSE, MASSACHUSETTS, ASSIGNOR OF ONE-HALF TO JESSE B. THOMAS, OF BOSTON, MASSACHUSETTS.

CHEMICAL FIRE-EXTINGUISHER.

SPECIFICATION forming part of Letters Patent No. 752,399, dated February 16, 1904.

Application filed October 12, 1903. Serial No. 176,602. (No model.)

To all whom it may concern:

Be it known that I, ALFRED J. KNIGHT, a citizen of the United States, and a resident of Melrose, county of Middlesex, State of Massachusetts, have invented an Improvement in Chemical Fire-Extinguishers, of which the following description, in connection with the accompanying drawings, is a specification, like letters on the drawings representing like parts.

This invention relates to chemical fire-extinguishers, comprising main and auxiliary receivers, the latter within the former and containing sulfuric acid or equivalent substance, which when discharged into the water and carbonate of soda or other contents of the main receiver mixes therewith and generates carbonic-acid gas. A portable fire-extinguisher of this type is shown and described in United States Patent No. 537,421, granted to me, and another April 9, 1895.

It is the usual practice to fill the main receiver or "canister," as it is often termed, with water and carbonate of soda until the level thereof is as high as possible with relation to the discharge-opening of the auxiliary receiver or acid-receptacle in order to utilize the greatest capacity and power of the apparatus. When such an extinguisher is standing upright and at rest on the floor of a room or on a shelf, there is no danger of any accidental mixing of the normally separated acid and alkaline contents, but when the extinguisher is carried about on a moving support—such as a wagon, car, boat, or other moving vehicle—the motion thereof agitates the contents of the main receiver and the resultant splashing or slopping tends to throw more or less of the alkaline liquid upon the discharge-opening of the acid-receptacle. Should any commingling of acid and alkali occur, (and it is practically impossible to prevent it under such circumstances,) gas will be generated in the main receiver. While this gas may pass off through the outlet without material damage, it will be obvious that both the acid and alkaline contents of the extinguisher have been weakened by the chemical combination, and this slight weakening of the charges may continue from

time to time until when the extinguisher is put into actual use its power may have been substantially dissipated. There is no way to discover this loss of power unless the extinguisher is opened and examined, and after it has been charged it should not be opened until after its contents have been discharged by use. If the outlet has a shut-off cock, the improper generation of pressure referred to tends to drive some of the alkali into the valve, so that the latter will stick and refuse to open when it is desired to use the extinguisher.

Various fire-department apparatus—such as engines, protective and hose wagons, ladder-trucks, &c.—are now commonly equipped with portable extinguishers, and the practice is increasing to provide them for cars and boats. In such equipment in addition to the generation of gas referred to the splashing or slopping of the contents of the canister or main receiver tends to throw small quantities of the liquid into the outlet, whence the liquid trickles out through the hose and spoils any painted surface with which it contacts.

My present invention has more especial reference to fire-extinguishers of the portable type referred to; and it has for its main object the production of means for preventing any objectionable results from agitation or splashing of the contents of the extinguisher during transportation from place to place. This and other novel features of my invention will be fully described in the subjoined specification and particularly pointed out in the following claims.

Figure 1 is a vertical section, centrally broken out, of a fire-extinguisher embodying one form of my invention, the auxiliary receiver and its closure being shown in elevation. Fig. 2 is a similar view but showing the extinguisher inverted, as it would be when in use. Fig. 3 is a sectional view similar to Fig. 1, showing a modification of the means for supporting the auxiliary receiver within the main receiver; and Fig. 4 is an under side view of the diaphragm, to be described.

In the present embodiment of my invention the main receiver or canister A, of suitable shape and construction, is provided with a base

A^x, Fig. 1, upon which it rests when not in use in normal upright position, said receiver at its end opposite the base having a filling-opening surrounded by an upturned flange a⁵, exteriorly threaded to receive a screw-threaded cap C. The cap is provided with an outlet for the receiver, (shown as a conduit or passage c,) having its inlet c' at the center of the cap, the discharge end of the outlet having a tubular continuation c², to which is attached a flexible hose a², provided with a suitable nozzle. Below the filling-opening the receiver A has secured to its inner walls a transverse diaphragm a⁵, herein shown as having several small perforations a⁶ and provided with a central opening a⁷, Fig. 4, the circular edge of the opening at the upper end of a depending sleeve a⁸ forming an annular seat a⁸, the diaphragm being higher than the proper level of the liquid contents of the canister A when in normal upright position. Surrounding the seat a⁸ are a number of large holes or perforations a^x, through which the liquid in the receiver A feeds when the extinguisher is in use, the small perforations a⁶ serving as drainage-outlets, as will be described.

The auxiliary receiver or acid-receptacle D in Figs. 1 and 2 is shown as a bottle, preferably made of glass and enlarged to form an annular laterally-projecting shoulder d^x, the body of the bottle being of such external diameter as will easily pass through the seat a⁸ and depending sleeve a⁹. The shoulder d^x rests upon the seat, and the auxiliary receiver D is thereby supported by the diaphragm in upright position, the neck d of the said receiver projecting upward beneath the inlet end c' of the canister-outlet c. When the extinguisher is not in use, the shoulder d^x projects over and covers the feed-apertures a^x, the dotted circle in Fig. 4 indicating the outer edge of the shoulder of the receptacle D at such time. The depending sleeve a⁹ easily receives the body of said receptacle and prevents any lateral or tipping movement thereof during transportation of the extinguisher, and the apertures a^x are also maintained covered or closed. A tubular holder h, shown as provided with perforations h^x and an internal shoulder h', depends from the cap C, secured thereto by being screwed onto an externally-threaded boss c^x. I have shown the perforations arranged in two rows, the upper one close to the boss and the lower row somewhat below the shoulder h' for a purpose to be described. The lower end of the holder surrounds the neck of the auxiliary receiver D and extends far enough downward when the cap C is in place to prevent the said receiver from jumping up away from the diaphragm a⁵, so that movement of the extinguisher from place to place cannot dislodge the receiver D, and, as shown in Fig. 2, the receiver is properly supported by the holder 65 when the extinguisher is inverted for use.

The discharge-opening for the auxiliary receiver, at the end of the neck thereof, is closed by a stopper or closure e, having oppositely-extended projections e e², the latter extending into the neck of the receiver, and an annular chamber e⁵ is formed in the lower side of the closure, inclosed by a depending lip e⁶, adapted to fit around the neck, the closure forming a tight joint with the neck when closed. The closure is substantially such as shown in United States Patent No. 598,826 and operates as therein set forth. As shown in Fig. 1, the projection e' of the closure extends upward part way through a stop, shown as a plate h¹⁰, seated on the seat h' of the holder and having a central opening h¹², into which the projection extends. Preferably the stop is concaved on its lower side to conform to the shape of the closure when the extinguisher is in use. The body of the closure slides freely within the holder h and is guided thereby in its opening and closing movements.

From an inspection of Fig. 1 it will be seen that the inlet-opening c' of the outlet of the main receiver is guarded or protected in a two-fold manner from entrance of the liquid contents of receiver A—viz., by the diaphragm a⁵ and the tubular holder h. If the contents of the receiver A are agitated and thrown about by transportation of the apparatus, the diaphragm first acts to prevent splashing or slopping in any material quantity beyond it, for only very small portions of the liquid, if any, can be thrown up through the perforations a⁶. As to such small portions of liquid which may pass up through the diaphragm they are prevented from entering the inlet by the tubular holder h and are broken into drops by contact therewith, and should any drops of the liquid enter the perforations h^x their upward impulse is dissipated, and they trickle back to the main body below the diaphragm. In the same manner the diaphragm and holder guard the discharge-opening of the auxiliary receiver, even should the closure e jump up or vibrate by reason of the movements of the extinguisher, and consequently the acid and alkaline contents of the two receivers cannot mix and combine.

When the extinguisher is inverted for use, as shown in Fig. 2, the gravity-closure e drops away from the neck d of the auxiliary receiver and its opening movement is limited by the stop h¹⁰, while the receiver D is permitted to drop a less distance against the end of the holder to remove the shoulder d^x from the diaphragm and to fully open the apertures a^x for the passage of liquid therethrough to feed to the outlet. The relative positions of the mouth of the neck d and the chambered side of the closure e are then such that the flow of the acid is gradual, charging the solution in the main receiver A evenly throughout substantially the entire operation, as described in Patent No. 598,826.

It will be observed that when the extinguisher is inverted, as in Fig. 2, the solution in receiver A can pass with all desired speed and in requisite quantity through the apertures a^x and central opening a^7 of the diaphragm and into the holder h through the perforations h^x thereof. Thence the gas generated and the water pass through the inlet c' into and through the outlet c to the hose a^8 and are directed therefrom to the desired points.

The means described for preventing objectionable results due to splashing or slopping of the solution in the receiver A is so efficient that the jarring and shaking incident to rapid travel of steam or electric cars or movement of fire apparatus through the streets has no injurious effect upon the extinguisher described herein.

In Fig. 3 I have shown a modified supporting device for the acid-receptacle B, which is shown as a bottle of ordinary construction having a neck b closed by the closure e . The receiver A, cap C, holder h , and stop h^{10} are substantially as hereinbefore described, and the main receiver is provided with a perforated diaphragm a^{10} , having a central opening a^{12} , substantially as described; but the diaphragm is slightly arched. A number of large feed-apertures a^{20} surround the opening a^{12} , and smaller drainage-apertures a^{25} are made in the diaphragm, as before described in reference to Figs. 1, 2, and 3. A metallic tubular carrier f , having a perforated bottom f' , is provided with an external annular flange f^2 , which rests upon the diaphragm and normally closes the apertures a^{20} . The main portion of the carrier depends below the latter, while the upper end f^3 of the carrier is shown as extended above and surrounding the lower end of the holder h , and the bottle is inserted in the carrier, the latter in turn being removable from the diaphragm. If any of the solution finds its way over the top of the carrier, it drains down through the perforated bottom f' , and when the extinguisher is inverted the drop of the bottle is limited by the holder h , while the bottom of the bottle prevents displacement of the carrier.

In either of the constructions shown the small apertures of the diaphragm serve to permit the liquid to drain back to the main body if the charge in the extinguisher is not completely discharged, as is sometimes the case.

My invention is not restricted to the precise construction and arrangement shown and described, as the same may be modified or rearranged by those skilled in the art without departing from the spirit and scope of my invention.

Having fully described my invention, what I claim as new, and desire to secure by Letters Patent, is—

1. A portable fire-extinguisher comprising a main receiver having an outlet, a filling-open-

ing at one end, and a perforated diaphragm 65 below it, an auxiliary receiver removably supported by said diaphragm, a cap to close the filling-opening, provided with a depending tubular and perforated holder to retain the auxiliary receiver in place, a gravity-closure 70 for the latter, movable within and guided by said holder, and a stop to limit the opening movement of the closure.

2. A portable fire-extinguisher comprising a main receiver having an outlet, a filling-opening at one end, and a perforated diaphragm below it, provided with a central opening, an auxiliary receiver removably supported within the opening, a gravity-closure for such receiver, a cap to close the filling-opening, and means to guide the movements of the closure and also to prevent displacement of the auxiliary receiver when the extinguisher is in use.

3. A portable fire-extinguisher comprising a main receiver having a filling-opening at one 85 end and a perforated, centrally-open diaphragm below it, an auxiliary receiver extended through the opening of and removably supported by the diaphragm, a gravity-closure for the auxiliary receiver, a cap to close 90 the filling-opening, having an outlet and provided with a depending perforated holder to engage the auxiliary receiver and prevent its displacement when the extinguisher is in use, said holder also guiding the closure in its 95 opening and closing movements, and an annular stop within the holder to limit opening movement of said closure.

4. A fire-extinguisher comprising a normally upright main receiver having a filling-opening and an outlet at its upper end, a transverse, perforated diaphragm below said filling-opening and having a central opening, an auxiliary receiver removably supported by the diaphragm and seated within the opening 100 thereof, a cap to close the filling-opening, having a depending perforated holder communicating with the outlet and adapted to limit movement of the auxiliary receiver from its seat on the diaphragm, a gravity-closure for 105 such receiver, guided by said holder, and means on the latter to limit opening movement of the closure.

5. A fire-extinguisher comprising a normally upright main receiver having a filling- 115 opening and an outlet, a cap to close said opening, an auxiliary receiver supported within the main receiver, a gravity-closure for the auxiliary receiver, separate means to protect the discharge-opening of the latter from 120 splashing of the contents of the main receiver when not in use, said means also constituting a support for the auxiliary receiver, and a device to limit movement of the same relatively to said means when the extinguisher is in use.

6. A fire-extinguisher comprising a main receiver, a normally upright acid-receptacle contained therein, a closure for the discharge-

opening of said receptacle, separate means to prevent the contents of the main receiver from splashing or being thrown upon the discharge-opening of the acid-receptacle when the extinguisher is not in use, said means also constituting a support for and relatively to which the acid-receptacle is movable, and a device to limit such movement and prevent displacement of said receptacle when the extinguisher is in use.

7. A fire-extinguisher comprising a canister having a filling-opening at one end, and an outlet for the contents of the extinguisher when in use, a perforated diaphragm below the filling-opening, having a central annular seat, an acid-receptacle supported on the seat and having a normally upturned discharge-opening, a gravity-closure therefor, a cap to close the filling-opening, a tubular perforated holder depending from the cap, to coöperate with and limit movement of the acid-receptacle, and also to guide the closure therefor, and an annular stop within the holder to limit opening movement of the said closure.

8. A fire-extinguisher comprising a normally upright canister having an outlet, and a filling-opening at its upper end, a closing-cap for the opening, an annular seat in and secured to the canister below the filling-opening, an acid-receptacle adapted to project through the seat and having an overhanging shoulder to rest thereupon, a depending tubular holder sustained by the cap and adapted to engage the acid-receptacle and limit its movement when the extinguisher is inverted for use, and a gravity-closure for the discharge-opening of the acid-receptacle.

9. A fire-extinguisher comprising a normally upright canister having an outlet, and a filling-opening at its upper end, a transverse, perforated diaphragm secured within the canister below said opening and having a central annular seat, and adjacent feed-apertures, an acid-receptacle extending partly through said seat and having an annular shoulder to rest thereupon, and normally close the feed-apertures, a gravity-closure for said receptacle, a cap to close the filling-opening, and a holder depending therefrom to engage and limit movement of the acid-receptacle when the extinguisher is in use and also to guide the gravity-closure in its movements.

10. A portable fire-extinguisher comprising a main receiver having an outlet, a filling-opening at one end, a diaphragm below it provided with a central opening and feed-apertures, an auxiliary receiver removably supported within the opening, a gravity-closure for such receiver, a cap to close the filling-opening, means to normally close the feed-apertures, and means to retain the auxiliary receiver in position on the diaphragm and also to guide the movements of the closure.

11. A fire-extinguisher comprising a canis-

ter having a filling-opening at one end, a cap to close the same, provided with an outlet for the contents of the extinguisher, a perforated diaphragm below the filling-opening, having a central annular seat and adjacent feed-apertures, an acid-receptacle supported on the seat and having a normally upturned discharge-opening, a gravity-closure therefor, a tubular perforated holder depending from the cap, to limit movement of the acid-receptacle when the canister is inverted and also to guide the closure therefor, means to normally close the feed-apertures in the diaphragm, and a stop within the holder to limit opening movement of the closure.

12. A fire-extinguisher comprising a canister having a filling-opening at one end, a cap to close the same, provided with an outlet for the contents of the extinguisher, a perforated diaphragm below the filling-opening, having a central annular seat and adjacent feed-apertures, an acid-receptacle adapted to project through the seat and having an overhanging shoulder to rest thereon and close the feed-apertures, a depending tubular holder sustained by the cap and adapted to limit movement of the shoulder from the diaphragm, and a gravity-closure for the discharge-opening of the acid-receptacle, guided in its movement by the holder.

13. A fire-extinguisher comprising a canister having an outlet, and a filling-opening, an annular seat fixedly mounted within the canister below its upper end, an acid-receptacle adapted to extend part way through the seat and having an overhanging portion to rest thereupon, a gravity-closure for the discharge-opening of the acid-receptacle, and means to guide the opening and closing movement of said closure, and also prevent displacement of the acid-receptacle when the extinguisher is inverted for use.

14. In a fire-extinguisher, a normally upright canister having an outlet, an annular seat fixedly mounted within the main body portion of the canister below its upper end, a removable acid-receptacle having an overhanging portion to rest upon the seat, the body portion of said receptacle entering and depending below the seat, and means to engage the enlarged and overhanging portion of and prevent displacement of the acid-receptacle when the extinguisher is inverted for use.

15. In a fire-extinguisher, a normally upright canister having an outlet, a cap to close the upper end of the canister, a centrally-open diaphragm secured within the main body portion of the canister below its upper end and having a series of feed-apertures arranged adjacent to its central opening, a removable acid-receptacle to extend part way through the central opening and having an annular overhanging shoulder to rest upon the diaphragm and close the feed-apertures, a gravity-clo-

sure for the discharge-opening of the acid-receptacle, and means connected with the cap and depending therefrom to limit movement of the acid-receptacle relative to the dia-
5 phragm when the extinguisher is inverted, such movement of the acid-receptacle causing the shoulder to uncover the feed-apertures.

In testimony whereof I have signed my name to this specification in the presence of two sub-
scribing witnesses.

ALFRED J. KNIGHT.
